UNITED STATES PATENT OFFICE.

OSKAR ARTHUR GÜNTHER, OF CHEMNITZ, GERMANY, ASSIGNEE TO CARL HÄMEL
ACTIEN-GESELLSCHAFT, OF SCHÖNAU, NEAR CHEMNITZ, GERMANY.

SPINNING-TRAY FOR CELLULAR-MATERIAL-SPINNING MACHINES.

1,134,379.

Specification of Letters Patent. Patented Apr. 6, 1915.

Application filed December 20, 1912. Serial No. 807,987.

To all whom it may concern:

Be it known that I, OSKAR ARTHUR GÜNTHER, of Chemnitz, Germany, a subject of the King of Saxony, and whose post-office address is 68 Weststrasse, Chemnitz, Kingdom of Saxony, German Empire, have invented new and useful Improvements in or Relating to Spinning-Trays for Cellular-Material-Spinning Machines, of which the following is a specification.

On the usual spinning trays for cellular material spinning machines, devices are known in which the lid closed on all sides, is secured to the spinning tray by a bayonet joint, and there are also in existence spinning trays in which the lid is divided and provided with a hinge, one half being secured to the spinning tray, while the other half is foldable and can be held closed by a pressure button with a spring. The first construction however has the drawback that the introduction of new disks of cellular band is very complicated and takes a long time, as the lid becomes jammed to the spinning tray owing to the bayonet closing device, and can be separated only by the use of considerable force by both hands. The second construction makes it possible to introduce only disks of cellular material strips, which are of a considerably smaller diameter than the inside diameter of the spinning tray. As the disk of cellular fabric does not take up a central position in the tray, but is driven to the side, the spinning tray is given a center of gravity which, at the high revolutions of the tray, causes vibrations of the spindle and therefore affects the revolutions of the latter and also the twist of the paper yarn. Both constructions with spinning trays closed on all sides, have moreover the drawback that the cellular material strips cannot be watched during spinning, and in case of a breakage of the band or thread, the introduction of the cellular material band is complicated. These drawbacks are obviated by the present invention, in which the lid of the spinning tray rests on the spinning tray merely as a bridge or is let in into the edge of the tray, and thus guided.

In removing the bridge of the spinning tray it is sufficient, after the spinning tray has been stopped, to exercise a pressure with

the thumb and index of the left hand in order to disconnect the lock and to remove the lid, while the disk of a cellular material strip is introduced with the right hand, and the free end of the band passed through an opening of the lid. In that way, the loosening of the lid of the spinning tray and the introduction of the roller or band are simplified to such an extent that even unskilled women can quickly attend to the machines. As the lid of the spinning tray is not completely closed, but merely formed into a bridge, the women can watch how far the disks of cellular material have been used up and can provide for spare ones.

A construction of a spinning tray bridge with its locking device is illustrated in the accompanying drawing, in which—

Figure 1, shows the spinning tray in cross-section and Fig. 2, in plan.

The known spinning tray consists of a flexible spiral 1, also known, and of the bottom part 2 of the spinning tray. In the edge of the spinning tray 2 two recesses are provided guiding the bridge 3. The bridge is cast with two lugs 4 provided with round pins 5 which exercise a drag on the band 8 of cellular material as it is drawn therethrough from the rapidly spinning tray. As is well understood in the art, the rapid rotation of the spinning tray twists the band into a thread as it passes between the pins 5 and inasmuch as this thread passes from one side to the other of said pins, a desirable degree of tension is provided in the thread. The lugs 4 are provided with two bosses 6 which are provided with bolts and form pivot points for the grip levers 7, the lower arm of which is pivoted to the bolts 8. The guide plates 9 mounted on the bridge 3, afford guidance to the bolts 8.

In order that the locking device should act by the centrifugal action of the bolts 8 and of the grip levers 7, the right hand grip lever is connected to the left bolt, and the left hand grip lever to the right hand bolt. By exercising a pressure on the two levers 100 in the direction of the axis of the spinning tray, the locking device is unlocked, and the bridge 3 can be removed, so that the opening or orifice of the spinning tray is uncovered. If the device is to be closed, the grip levers 7 are pressed outward.

Applicant's co-pending case 807,938 shows a tray of this type as used in the complete machine.

What I do claim as my invention, and desire to secure by Letters Patent of the United States, is—

1. A spinning tray provided with a removable bridge, locking bolts slidably mounted on said bridge to be moved into and out of locking engagement with said tray, and levers mounted on said bridge to swing radially relatively to the axis of rotation of said spinning tray, said levers being respectively connected to said locking bolts, the connections between said levers and bolts being adapted to apply the centrifugal force of said levers to holding said bolts in locking position.

2. A spinning tray provided with a removable bridge, a boss raised in the middle portion of said bridge, two levers pivoted to said boss, bolts slidable radially with respect to the axis of rotation of said tray, and pivoted at their inner ends respectively to the lower ends of said levers, the larger part

of the mass of said bolt being eccentric to said axis to hold the bolt in locked position by centrifugal force.

3. A spinning tray provided with a removable bridge, a boss raised in the middle portion of said bridge, two levers pivoted to said boss, bolts slidable radially with respect to the axis of rotation of said tray and pivoted at their inner ends respectively to the lower ends of said levers, the larger part of the mass of said bolt being eccentric to said axis to hold the bolts in locked position by centrifugal force, and each of said levers being adapted by its arrangement to impart a thrust to its connected bolt in a direction to hold it in locked position due to centrifugal force.

In testimony whereof I have hereunto set my hand in presence of two subscribing witnesses.

OSKAR ARTHUR GÜNTHER.
